UNITED STATES PATENT OFFICE.

JOHN GILMOUR, OF OWENSBORO, KENTUCKY.

MACHINE FOR MAKING CASKS.

No. 920,730.

Specification of Letters Patent.

Patented May 4, 1909.

Application filed June 11, 1908. Serial No. 437,875.

To all whom it may concern:

Be it known that I, JOHN GILMOUR, a citizen of the United States, resident of Owensboro, in the county of Daviess and State of Kentucky, have made a certain new and useful Invention in Machines for Making Casks; and I declare the following to be a full, clear, and exact description of the same, such as will enable others skilled in the art to which it appertains to make and use the invention, reference being had to the accompanying drawings, and to the characters of reference marked thereon, which form a part of this specification.

The invention relates to machines for making casks, having for its object the provision of a machine of simple and efficient character whereby tobacco hogsheads may be readily set up from the loose staves and the binding hoops secured therearound by an unskilled person or boy.

Other objects and advantages will herein-after appear.

The invention consists in the novel construction and combinations of parts as herein-after set forth.

In the accompanying drawings, illustrating the invention, Figure 1 is a plan view of the machine, showing the front section of the 30 stave holder turned outward in dotted lines, and showing the staves of the lower half of the cask in position in the machine; Fig. 2 is a section on the line $x-x$, Fig. 1, with all of the staves of the cask shown as in position 35 in the machine and showing the hoop tightener as applied; Fig. 3 is a similar view, the staves of the lower half of the cask only being shown as in position in the machine and the hoop tightener not being shown; Fig. 4 is a front view of the machine showing the front sections of the stave holders turned outward in dotted lines; Fig. 5 is a detail longitudinal section of the slot and bolt connection for the end portions 40 of the central inner hoop; Fig. 6 is an end view of the machine showing the staves of the lower half of the cask in position therein, and showing the devices for decreasing the diameter of the stave holder in forming casks 45 of smaller size; Fig. 7 is a detail sectional view on the line 7-7 of Fig. 6.

In these drawings the letter a , designates a platform or base upon which the machine is mounted. At each end of the base is provided a stave holder and tightener b , of an-

nular or ring form, each such device being formed in two semi-circular sections c , and c' , having a hinged connection d , at the bottom thereof. The rear section c , at each end, is rigidly supported from the base by horizontal top and bottom tangential arms e , e' , and a vertical arm or standard f , connecting the arms e , e' . The forward section c' , is hinged at its bottom end to the section c , at d , as before stated, and at its upper or free end is provided with a perforation c^2 . A tightening lever g , is fulcrumed at its lower end to the section c , at each end, near the upper end thereof, and has flexible connection g' , with the upper end of the hinged section c' , a hook 70 end h , of such flexible connection engaging the perforation c^2 . The lever g , has pawl engagement with the teeth of rack i , for the purpose of maintaining the lever and section c' , at each end in position as adjusted. 75

The loose staves are dropped or inserted into the machine at the top thereof around an inner supporting annulus j , located centrally of the machine, and are held in position upon the outside by the stave holders b , b , at 80 each end of the machine. That is to say the lower staves are inserted into position upon the end holders, until they form the lower half of the hogshead, when the inner ring is placed in position and the remaining half 85 of the hogshead built up. The sections of the end holders are then tightened upon the staves by the levers and flexible connections referred to, when the bilge hoops are ready to be placed and tightened in position by the 90 means now to be described.

Each bilge hoop k , comprises preferably a flat band of sheet metal or it may be of wood, one end k' , of which is first nailed to the hogshead at k^2 , the other end l , being detachably secured in a cam clamp l' , having flexible connection m' , with a lever m , such lever having a pointed metal end m^2 , capable of engagement with the hogshead, whereby when drawn or pulled downward the loose 100 end of the hoop will be brought toward and lapped with the nailed or fast end thereof and the hoop tightened upon the hogshead, when it may be nailed upon the fast end or adjacent thereto. The bilge hoops having 105 been applied as aforesaid the hogshead is complete with the exception of the heads, which may be readily placed and secured in position, the inner ring j , being first removed. The flat body portion l' , of the clamp l' , is 110

substantially in line with the loose end of the hoop k , when the device for tightening the hoop is in use.

In order that hogsheads of varying size 5 may be set up the inner supporting annulus j , has its ends normally separated by an interval j' , and connected by side pieces j^2 , having bolt connection o, o , with one end of the hoop, and slot and bolt connection o', o^2 , 10 with the other end of the hoop, whereby when desired the ends may be pushed together to contract the hoop for smaller hogsheads and the bolt o' , tightened to secure the hoop in position as adjusted. When this smaller 15 size of hogshead is to be built an annular, inch-thick piece p , is bolted to the inside of the sections c, c' , at each end of the machine, as shown in Figs. 6 and 7 of the drawings. Owing to the spring character of the central 20 inner stave supporting annulus it yields or the ends thereof approach each other when the staves are inserted in the machine for the hogshead of usual or ordinary size, thus preventing the staves from slipping past each 25 other.

When the hogshead is ready to be removed from the machine the movable section c' , is turned horizontally upon the vertical hinge pin connection with the section c , as shown 30 in Figs. 1 and 4 of the drawings, allowing the hogshead to move forward and out of the machine. In order that the sections c, c' , may be readily turned horizontally for this purpose the end holders of which they form 35 a part are located quite close to the ends of the hogshead to be built, the distance separating such holders being but little less than the length of the staves.

The devices for tightening the bilge hoops, 40 including the lever m , having a pointed metal end for engagement with the hogshead and a flexible connection intermediate thereof with the clamp device for the free end of the hoop, may be used without

the machine proper for tightening and securing hoops upon a barrel in substitution for a broken hoop or hoops thereof.

Having described the invention, what I claim and desire to secure by Letters Patent is:

1. In a machine for making casks, a base, outside supporting and tightening means for the staves including a rigid semi-circular member, a pivoted semi-circular member capable of swinging upon the chord of its arc 55 as a center, means for adjusting the pivoted member toward the fixed member, and inside supporting means for the staves.

2. In a machine for making casks, a base, outside supporting and tightening means for 60 the staves including a rigid semi-circular member, a pivoted semi-circular member capable of swinging upon the chord of its arc as a center, a lever device having a flexible connection with the pivoted member for adjusting the same toward the fixed member, 65 means for fixing the lever adjustment, and inside supporting means for the staves.

3. In a machine for making casks, a base, outside supporting and tightening means for 70 the staves including a rigid semi-circular member, a pivoted semi-circular member capable of swinging upon the chord of its arc 75 as a center, a lever device having a flexible connection with the pivoted member for adjusting the same toward the fixed member, means for fixing the lever adjustment, inside supporting means for the staves, and inner detachable semi-circular strips having 80 connection with the fixed and pivoted members.

In testimony whereof I affix my signature, in presence of two witnesses.

JOHN GILMOUR.
